UNITED STATES PATENT OFFICE.

LESTER J. CHASE, OF BUFFALO, NEW YORK.

FIRE-ESCAPE LADDER.

SPECIFICATION forming part of Letters Patent No. 430,173, dated June 17, 1890.

Application filed January 4, 1890. Serial No. 335,908. (No model.)

To all whom it may concern:

Be it known that I, LESTER J. CHASE, a citizen of the United States, residing at Buffalo, in the county of Erie and State of New York, 5 have invented certain new and useful Improvements in Fire-Escape Ladders; and I do hereby declare the following to be a full, clear, and exact description of the invention, such as will enable others skilled in the art 10 to which it appertains to make and use the same.

This invention relates to a portable flexible ladder to wind on a drum and used for fire-escapes or other purposes against the 15 sides or front of buildings; and it consists in the combination and arrangement of the parts and in certain features to be hereinafter fully explained.

In the drawings, Figure 1 is a side elevation of the device in position; Fig. 2, one side of lower part enlarged, showing frame and part of ladder; Fig. 3, one side of ladder enlarged with frame removed; Fig. 4, a side view of one section of ladder detached and joint-cover; Fig. 5, a front view of one section of ladder detached; Fig. 6, a top view of same, showing position of slide or joint cover.

A represents the metal frame supporting in suitable bearings a large drum B, around 30 which a jointed ladder C winds by means of a crank. On one side of the drum B is a cog-wheel, which meshes into a cog-wheel c of a drum or frame journaled in frame A just above and a little back of drum B. This in turn meshes into a smaller cog-wheel d, journaled in the top of the frame A, having cog-wheels at both ends of its shaft.

The ladder C consists of a series of sections f f, hinged together at e e, each having 40 a metal ring in the middle, (see Figs. 4, 6, and 7,) said section sides being cut away at the corners for winding purposes. The outsides of the ladder-sections are provided with a cogged rack, into which the cogs of the 45 wheel d mesh. These by operating the crank unwind and run up the ladder or wind it on drum B.

A pressure-roller m is set in the frame A at each side in contact with the under side 50 of the ladder-rack and opposite cog-wheels d.

To make the ladder rigid at the joints as it goes up and hold it so, the inside lower half of the ladder-sections f f are provided with a metal covering piece or slide g, the edges being bent over the outside edges of the ladder-sections f f and adapted to slide down over the joints or hinge e of its own and the next section. This is accomplished as follows: In the sides of the frame A, just below the cog-wheel d and opposite each other, are 60 two triangular-shaped dogs h h', pivoted in the frame, the inside dog h pivoted at its lower end and the outside one h' pivoted at its upper end. Springs i at the other end of each keep the dogs in position, as shown in 65 Fig. 3. Each side piece of each rung of the ladder is first cut away at the inside corners to admit of winding on the drum, as before stated, and the inside at the upper end is cut away a short distance into a notch n, and 70 the lower back part is cut out into a similar notch n'. As the ladder goes up, the projecting free end of the inside dog h strikes against the upper edge or end of the slide g and forces it down over the joint e until it strikes 75 and rests in the notch n of the side piece f, the spring of the dog keeping it in position for the next slide, and so on, the same on both sides of the ladder. To throw these slides all back in their normal position when 80 the ladder is drawn down and wound up the opposite spring-dog h' comes in play. It being in reversed position to dog h, its projecting free end catches under the end of the slide g and pushes it upward until the 85 upper end of the slide rests on the notch n' in the back of side piece f, and so on throughout the ladder. This is very simple and effective, and the whole ladder is without complication. 90

The entire device may be stationary or made movable, if desired, by putting it on wheels.

I do not claim, broadly, a jointed ladder operated by cogs adapted to be wound on a 95 drum and its sections or hinges locked, as such are old.

I claim—

In a fire-escape, a ladder made flexible and adapted to be wound on the drum B, hav- 100

ing the sectional side pieces *ff* cut away at
n n', adapted to receive the joint-covering
slides *g g*, and the spring-dogs *h h'*, pivoted
in the frame A, adapted to act on said slides
5 to cover and uncover the joints *e e* of said
ladder, all substantially as and for the pur-
pose specified.

In testimony whereof I affix my signature
in presence of two witnesses.

LESTER J. CHASE.
